UNITED STATES PATENT OFFICE

147,588

DESIGN FOR A FIGURED BAG FOR DUST
CLOTHS

Sholom E. Kaplan, Hartford, Conn.

Application October 9, 1945, Serial No. 122,683

Term of patent 14 years

(Cl. D58—2)

To all whom it may concern:

Be it known that I, Sholom E. Kaplan, a citizen of the United States, residing at Hartford, in the county of Hartford, State of Connecticut, have invented a new, original, and ornamental Design for a Figured Bag for Dust Cloths, of which the following is a specification, reference being had to the accompanying drawing, forming a part thereof.

In the accompanying drawing the figure is a perspective view of a figured bag for dust cloths, embodying my design.

The characteristic features of my design reside in the specific surface ornamentation on the front of the bag, as shown.

I claim:

The ornamental design for a figured bag for dust cloths, substantially as shown and described.

SHOLOM E. KAPLAN.
